UNITED STATES PATENT OFFICE

RALPH W. FRAMBACH, OF MAPLEWOOD, NEW JERSEY

DESIGN FOR A TEXTILE FABRIC OR THE LIKE

Application filed November 7, 1932. Serial No. 45,783. Term of patent 3½ years.

To all whom it may concern:

Be it known that I, RALPH W. FRAMBACH, a citizen of the United States, residing at Maplewood, Essex County, State of New Jersey, have invented a new, original, and ornamental Design for a Textile Fabric or the like, of which the following is a specification, reference being had to the accompanying drawing, forming part thereof.

The figure is a plan view of a piece of textile fabric, showing my new design.

The dot and dash lines on the drawing outline the design unit, which unit is repeated in regular succession, as indicated by the extensions beyond the unit boundaries.

I claim:

The ornamental design for a textile fabric or the like, as shown and described.

RALPH W. FRAMBACH.
